(57) **CLAIM**

The ornamental design for an airplane, as shown and described.

DESCRIPTION

I. FIGS. 1-6 show a first embodiment of our new and original design for an airplane, wherein

FIG. 1 is a perspective view thereof;

FIG. 2 is a front elevation view thereof;

FIG. 3 is a rear elevation view thereof;

FIG. 4 is a top plan view thereof;

FIG. 5 is a bottom plan view thereof; and

FIG. 6 is a left side elevation view thereof, the right side elevation view being a mirror image thereof;

II. FIGS. 7-12 show a second embodiment of our new and original design for an airplane, wherein

FIG. 7 is a perspective view thereof,

FIG. 8 is a front elevation view thereof;

FIG. 9 is a rear elevation view thereof;

FIG. 10 is a top plan view thereof;

FIG. 11 is a bottom plan view thereof; and

FIG. 12 is a left side elevation view thereof, the right side elevation view being a mirror image thereof;

III. FIGS. 13-18 show a third embodiment of our new and original design for an airplane, wherein

FIG. 13 is a perspective view thereof,

FIG. 14 is a front elevation view thereof;

FIG. 15 is a rear elevation view thereof;

FIG. 16 is a top plan view thereof;

FIG. 17 is a bottom plan view thereof; and

FIG. 18 is a left side elevation view thereof, the right side elevation view being a mirror image thereof; and

IV. FIGS. 19-24 show a fourth embodiment of our new and original design for an airplane, wherein

(Continued)

FIG. 19 is a perspective view thereof;
FIG. 20 is a front elevation view thereof;
FIG. 21 is a rear elevation view thereof;
FIG. 22 is a top plan view thereof;
FIG. 23 is a bottom plan view thereof; and,
FIG. 24 is a left side elevation view thereof, the right side
elevation view being a mirror image thereof.
